N. J. A. WAHLBERG,
STRUCTURE FOR TROLLEY WIRE FITTINGS
APPLICATION FILED AUG. 7, 1917.

1,374,537.

Patented Apr. 12, 1921.

UNITED STATES PATENT OFFICE.

NILS J. A. WAHLBERG, OF PITTSBURGH, PENNSYLVANIA, ASSIGNOR TO WESTINGHOUSE ELECTRIC & MANUFACTURING COMPANY, A CORPORATION OF PENNSYLVANIA.

STRUCTURE FOR TROLLEY-WIRE FITTINGS.

1,374,537.

Specification of Letters Patent. Patented Apr. 12, 1921.

Application filed August 7, 1917. Serial No. 184,806.

To all whom it may concern:

Be it known that I, NILS J. A. WAHLBERG, a subject of the King of Sweden, and a resident of Pittsburgh, in the county of Allegheny and State of Pennsylvania, have invented a new and useful Improvement in Structures for Trolley-Wire Fittings, of which the following is a specification.

My invention relates to trolley-line fittings and it has special relation to trolley-wire splicers, frogs, strain supporters and the like, in which the apparatus is subject to considerable wear and also deterioration because of arcing between the trolley wheel and the trolley-line fittings, and it has for its object to provide apparatus of the character designated which shall be simple and inexpensive to manufacture, durable in service, adapted to grip the wire firmly, and embodying a minimum number of loose parts to be handled by the linemen.

Referring to the accompanying drawings, Figure 1 is a plan view of a trolley-frog constructed in accordance with my invention. Fig. 2 is a sectional view of the apparatus shown in Fig. 1, the section being taken along the line II-II, of Fig. 1. Fig. 3 is a side elevational view of the apparatus shown in Fig. 1. Fig. 4 is a detail view of the approach member used in apparatus constructed in accordance with my invention. Fig. 5 is a side elevational view of a portion of a trolley-wire splicer embodying my invention.

Heretofore, it has been customary in constructing trolley line fittings, such, for example, as wire splicers and frogs, to either construct the entire device of some composition alloy, which is very expensive when the apparatus is of large size, or to attach an approach member to the apparatus by means of several stove bolts extending through lugs in both the apparatus and the approach member.

By my invention, I provide apparatus of increased strength at decreased cost, wherein the clamping effect is positive, the bearing surface is relatively large, and the approach members may be renewed when pitted or worn out.

Referring to the accompanying drawings, a main body portion 1 is provided with approach members 2, into which a trolley wire 3 extends. The approach member 2 is provided with a clamping por-

tion 4 which surrounds the trolley wire and a shoulder 5, which is adapted to bear upon the upper surface of the trolley wire 3. The main body portion 1 is provided with a groove 6, which is adapted to receive the trolley wire 3, and also with a lug 7 which projects over the groove 6. The lug 7 is adapted to receive a set screw 8 which engages the shoulder 5 of the approach member 2, clamping it against the trolley wire 3 which rests in the groove 6 of the main body portion 1.

While I have shown and described particular forms of my invention, changes may be effected therein without departing from the spirit and scope thereof, as set forth in the appended claims.

I claim as my invention:

1. A trolley-line device comprising a body member having a groove for the reception of a trolley conductor and an integral interiorly-threaded lug projecting laterally over said groove, a renewable approach member having a portion disposed in said groove between said lug and said conductor, and a set screw in said lug for clamping said approach member in position.

2. A trolley-line device comprising a body member for the reception of a trolley conductor having an interiorly-threaded lug extending transversely with respect to said conductor, a renewable approach member having a portion disposed between said lug and said conductor, and a set screw in said lug for clamping said approach member in position.

3. A trolley-line device for disposition at an intermediate portion of a trolley conductor comprising a body member having a portion disposed over the conductor, a renewable approach member having a portion disposed between the conductor and said first portion, and means coöperating between said portions for holding the approach member in position.

4. A trolley-line device for disposition at an intermediate portion of a trolley conductor comprising a body member having a groove for the reception of the conductor and an integral portion extending across said groove, a renewable approach member, and means coöperating between said integral portion and said approach member for securing the latter in position.

5. A trolley-line device comprising a body member having a groove for the reception of a conductor and an integral portion extending laterally over said groove from one side thereof, a renewable approach member having a portion extending into said groove between said integral portion and the con-

ductor, and means coöperating between said portions for clamping the approach member in position.

In testimony whereof, I have hereunto subscribed my name this 20th day of July, 1917.

10
NILS J. A. WAHLBERG.
